In France February 28, 1933

3 Claims. (Cl. 177—350)

This invention relates to advertising apparatus constituted by a board composed of juxtaposed elements the aspect of which can be modified (for instance, rotating lamps, shutters or mirrors); these elements can be set in action successively in any required order, in such a manner that the spectator has the impression that an invisible hand writes or draws on the board.

The invention has for its object to solve the technical problem which consists in automatically controlling the operation of these apparatus by means of perforated hands or the like.

The difficulty of this problem resides in the fact that at any moment any of the elements must be capable of being actuated; it appears therefore necessary that the perforated band should comprise as many series of perforations as there are elements, and this, in practice, is impossible. In fact, it is not possible to provide, for the control of an advertising board of 10,000 lamps for instance, a band sufficiently wide to be transversely perforated with 10,000 holes in a straight line.

The invention is characterized by the fact that the board is divided into several equivalent zones, the selection of a zone being effected by a series of perforations, whilst the selection of the elements of each zone is effected by another series of perforations.

In the above mentioned example of a board of 10,000 lamps, this board can for instance be divided into 100 zones of 100 lamps. The perforated band will then have a width reduced to that necessary for 200 perforations, instead of 10,000 perforations. It will therefore be 50 times less wide, and thus will be reduced to acceptable dimensions.

The accompanying drawings diagrammatically illustrate, by way of example only, a form of carrying the invention into practice.

Fig. 1 is a diagrammatic view of the entire apparatus.

Fig. 2 is a detail diagrammatic view.

The example of Fig. 1 shows a board composed of 81 elements distributed in nine zones each numbered from I to IX of nine elements each numbered, in each zone, from 1 to 9.

Each element constituted, for instance as shown in Fig. 2, comprises a lamp 10 which is lighted upon closing the contact 11 actuated by the armature of the relay 12. Holding contacts 12^a and 12^c are also actuated by the relay 12 and a contact 23 actuated by a magnet 22 initially energizes the relay 12. A contact 12^b is interposed in the holding circuit of the relay 12 and is opened by an electromagnet 35.

The circuit of the relay is controlled by two series of perforations 13 and 14 belonging either to two distinct bands driven in synchronism, or to one and the same band 15. The wire 16 is multiplied at 17 on each relay homologous to 12 in each zone (that is to say on each relay having the same number). The band 15 moves on a contact table 18 connected to one of the poles 19 of the source of energy 20, the other pole 21 of which is assumed to be grounded. The perforations 13 directly control the wire 16 leading to one terminal of the coil of the relay 12, but the perforations such as 14, so-called "zone perforations", control the wires 40 leading to one terminal of the coils of electromagnets 22. One electromagnet 22 is provided per zone, and the energization of said electromagnet closes all the contacts 23 connected to the relays 12 in the zone under consideration. The opposite end of the relay coil 12 is connected with the contact 12^c which normally engages a conductor 41 leading to the contact 23. The opposite end of the magnet coil 22 is grounded at 21^a. Thus, in the example illustrated, the circuit of the electromagnet 22 of the zone II is energized, and all the contacts 23 of this zone are closed. The perforation 13 closes, in this zone II, the circuit of the element 5, that is to say the electromagnet 12 of this element is energized. Consequently, the band 15, through the medium of the perforations 14, chooses a zone and, through the medium of the perforations 13, it chooses an element in this zone. The operation is as follows: The electromagnet 22 is energized on the passage of a perforation 14 and actuates the contact 23. During the simultaneous passage of a perforation 13, the relay 12 is energized by a circuit including the conductor 16, relay coil, contact 12^c, conductor 41, closed contact 23 and ground 21^a. Thus, the contact 11 is operated, closing the circuit of the lamp 10 over the conductor 42 and the ground connection 21^b. Simultaneously the holding contacts 12^a and 12^c are actuated, the contact 12^c establishing a connection between the relay 12 and the ground 21^b and the contact 12^a closing the other side of the circuit for the relay 12 over a conductor 43 connected with the pole 19 of the current source. The normally closed contact 12^b is interposed in the conductor 43 and the relay 12 is maintained in energized condition after the passage of the perforations 13 and 14 until the holding circuit is interrupted by opening the contact 12^b.

Then the band 15, continuing to move, will choose, by means of its two series of perforations 13 and 14, the next zone and the next element in this zone.

13 and 14, respectively, another element and either another zone, or the same zone, the operation taking place over again in this manner up to the end of the series of perforations.

5 It will be seen that the band 15 has a width corresponding to 18 holes, instead of necessitating a width corresponding to 81 holes.

The invention is not limited in any way to the very diagrammatic example which has just been 10 described. The elements can be other than lamps and, for instance, rocking or rotating shutters, or mirrors. They can be actuated electrically, pneumatically, or in any suitable manner. The perforated bands can be replaced by any equivalent 15 members used in other arts, such as pin drums or the like.

The apparatus can be devised in order to be actuated by hand (Fig. 2). In this case, the operator moves a contact 24, in the same way as 20 a pencil, on a board 25 divided into zones, each zone comprising as many contacts 26 as there are elements in a zone of the advertising panel. The movable contact 24 is mounted at the end of one of the branches of a pantograph 27, the 25 pivot 28 of which is connected to the pole 18 of the source of energy. The end of the other branch of the pantograph carries a contact 30 which moves on a board 31 divided into conducting zones insulated from each other, each zone such as 32 being connected by a wire 33 to the winding of the zone electromagnet 22 corresponding thereto.

The operation is as follows:

For actuating the device by hand, the contact 34 is closed, then, by means of the stylus 24, the operator draws on the board 25. The stylus 33 moves at the same time on the board 31. It will thus easily be seen that the suitable zone electromagnet 22 is energized by means of the stylus 33 40 and that, in this zone, the electromagnet 12, of the element corresponding to the contact 26 which is engaged at this moment by the stylus 24, is also energized. For causing the drawing to disappear, it suffices to open the contact 12b 45 (which may be done manually). This contact can, when the operation is automatic, be controlled by the perforated band 15. The latter would then be provided with a special perforation allowing to energize the electromagnet 35 50 which, when energized, pulls the contact 12b.

It is convenient that the zones should be of square shape, because in this way the passage from one zone to another is less frequent than if the zone had another shape.

55 The rapidity with which the drawing is effected can then be greater, since a number of switchings through the electromagnets 22 is avoided.

The use of the contacts 23 could have been 60 avoided by connecting all the elements of one

zone to one and the same wire, controlled by the series of perforations 14; but this arrangement is not convenient, for the reason that a large number of shunt circuits then exists, which circuits, although sufficiently resistant for preventing the energization of the elements included therein, produce however, owing to their number, a current of high intensity controlled by the perforations 14.

What I claim as my invention and desire to 10 secure by Letters Patent is:

1. An advertising apparatus comprising a plurality of similar groups of juxtaposed elements capable of presenting distinct rest and working aspects, the elements of one and the same group 15 being arranged one beside the other according to several lines in order that this group forms a square surface, an electromagnet for each element, means controlled by said electromagnet, for effecting the change of aspect, a source of electric energy, circuits fed by the said source of electric energy provided in a number equal to the number of elements of a group, each of these circuits comprising in shunt the electromagnets of the homologue elements of the various groups, means for selectively controlling said circuits in any sequence, a contact in each branch line arranged to be normally open, an electromagnet in each group for simultaneously closing and opening all the contacts of this group, means for selectively controlling the said electromagnets in any sequence, means for holding in their working position the elements moved to this position by energization of their electromagnets and means for subsequently restoring said elements to 30 their position of rest.

2. An advertising apparatus comprising a plurality of similar groups of display lamps, the lamps of one and the same group being arranged one beside the other according to several lines 40 in order that this group forms a surface, a source of electric energy, separate circuits for the lamps, a lamp contact in each of the said circuits, a lamp electromagnet for controlling each lamp contact, circuits provided in a number equal to 45 the number of lamps of a group, each of these circuits comprising in shunt the lamp electromagnets of the homologue lamp of the various groups, means for selectively controlling said circuits in any sequence, a contact in each branch 50 line arranged to be normally open, an electromagnet in each group for simultaneously closing and opening all the contacts of this group, means for selectively controlling the said electromagnets in any sequence, means for holding the 55 lamp electromagnets in their energizing position, and means for subsequently restoring said lamp electromagnets to their position of rest.
